(57) **CLAIM**

The ornamental design for a display screen with graphical user interface for a train operator control, as shown and described.

DESCRIPTION

FIG. 1 is a plan view of a display screen with graphical user interface for a train operator control showing our new design; and,

FIG. 2 is a plan view of a second embodiment thereof. The broken line showing of the remainder of the graphical user interface is included for the purpose of illustrating dynamic elements and forms no part of the claimed design.
